PIN CURL CLIP

Charles R. Cochran, Chicago, Ill.

Application January 3, 1945, Serial No. 571,129

4 Claims. (Cl. 132—46)

This invention relates to pin curl clips and it is primarily an object of the invention to provide a clip of this kind which will hold a pin curl in position during the drying process without mashing but in a manner to maintain the curl in its original form.

Another object of the invention is to provide a clip of this kind embodying a top member and a body member and wherein the top member is so formed as to provide a core which holds the center of the pin curl open.

Furthermore, it is an object of the invention to provide a pin curl clip constructed in a manner to assure speedy anchoring and effective holding of a pin curl close to the head and at the same time keeping the helical center of the pin curl open and generally maintaining said curl in its original contour.

In professional hair dressing, many small curls are formed and held in position close to the head by means of hair pins as a preliminary step in preparing the wave necessary in styling the hair. The hair pins required are very numerous, tedious to apply, and often distort the symmetry of the curls which, when combed out for styling, are difficult to form into the desired wave effect. A particular object of the invention is to provide a clip which will substantially eliminate these disadvantages.

The invention consists in the details of construction and in the combination and arrangement of the several parts of my improved clip whereby certain important advantages are attained and the article rendered simpler, less expensive and otherwise more convenient and advantageous for use, as will be hereinafter more fully set forth.

The novel features of my invention will hereinbelow be definitely claimed.

In order that my invention may be the better understood, I will now proceed to describe the same with reference to the accompanying drawing, wherein—

Figure 1 is a view in side elevation of a clip constructed in accordance with an embodiment of the invention;

Figure 2 is a view in perspective of the bottom member of the clip;

Figure 3 is a view in perspective of the top member of the clip;

Figure 4 is a sectional view taken substantially on the line 4—4 of Figure 1; and

Figure 5 is a view in perspective illustrating a clip constructed in accordance with another em-

bodiment of the invention, a pin curl being indicated by broken line.

In the embodiment of the invention as illustrated in Figures 1 to 4, the clip includes two members, A and B, the member A being the top of the clip and the member B the bottom.

The member A comprises an elongated flat bar 1 having its rear end continued by a perpendicularly related and relatively short handle member 2, and the opposite or forward end of the bar 1 is continued by a downwardly and forwardly inclined extension 4. The intermediate portion of the bar 1, and at approximately its center is depressed to provide a core or divider 5. The handle member 2, at its side margins and immediately adjacent to its junction with the bar 1, is provided with the rearwardly disposed ears 6 for a purpose to be hereinafter referred to.

The bottom or lower member B comprises a plurality of parallel flat teeth 7, herein disclosed as three in number. These teeth 7 are integral with a rear plate or head 8, which is provided with an upwardly and rearwardly inclined handle member 9, herein shown as on an approximate angle of 45° with respect to the plane of the teeth 7. The side margins of the handle member 9, at the central part thereof, are provided with the forwardly directed ears 10.

The ears 6 of the member A and the ears 10 of the member B partly overlap and through said overlapping portions of the ears 6 and 10 is directed a rivet pivot member 11 whereby the members A and B are connected for swinging movement one with respect to the other. The member 35 A is constantly urged toward the member B by a coil spring 12, encircling the pivot member 11 between the ears 6 and 10, said springs having extended end portions 12, one bearing against the handle member 2 and the other against the handle member 9.

Normally the members A and B are in closed relation with the core 5 in contact with the middle tooth 7 but by pressing together the handle members 2 and 9, the clip will be opened to allow the core to be applied. When applied, the core or divider 5 is within the helical opening of the pin curl while the perimeter of the curl is held between the middle tooth 7 and the portions of the bar 1 fore and aft of the core or divider 5. The extension 4 engages the curl in a manner to retain the same in required formation. The core or divider 5 is of such depth to prevent the upper member A from collapsing or mashing the pin curl with which the clip is used or otherwise distorting the regularity of the curl and thus holding

the pin curl securely yet free enough to allow fast drying.

In the embodiment of the invention as illustrated in Figure 5 the top member C and the bottom or lower member D are constructed and assembled in substantially the same manner as the members A and D, respectively, except that the bar 15 of the top member C forwardly of the core or divider 16 is formed to provide a plurality of outwardly and radially disposed arms 17 terminating in a downwardly and forwardly inclined extension 18. These arms 17 coat with the pin curl in the same manner as hereinbefore set forth with respect to the bar 1 comprised in the first embodiment of the invention.

From the foregoing description it is believed to be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A pin curl clip comprising two relatively long members, means connecting said members for relative swinging movement, means for constantly urging the members to closed position, one of the members being flat and of materially greater width than the other to form a base along the longitudinal center of which the other member extends, and a core carried by the other one of the members and disposed toward the said one thereof to space the portions of the other member fore and aft of the core from the one member when said members are in closed position, said core

member being adapted to be received within the central opening of a pin curl.

2. A pin curl clip comprising two relatively long members, means connecting said members for relative swinging movement, means for constantly urging the members to closed position, one of the members being flat and of materially greater width than the other to form a base along the longitudinal center of which the other member extends, and a core carried by the other one of the members and disposed toward the said one thereof to space the portions of the other member fore and aft of the core from the one member when said members are in closed position, said core member being adapted to be received within the central opening of a pin curl, the outer end portion of the member having the core terminating in an angled tip directed toward the second member.

15 3. A pin curl clip as set forth in claim 1 wherein the said one member comprises a plurality of substantially parallel wide, flat teeth.

4. A pin curl clip comprising two members, means connecting said members for relative swinging movement, means for constantly urging one of the members toward the other, a core carried by one of the members and disposed toward the other to space the portion of the one member fore and aft of the core from the second member when said members are in closed position, said core member being adapted to be received within a central opening of a pin curl, and the member carrying the core being provided in advance of the core with a plurality of outwardly and radially disposed arms for co-action with the pin curl with which the clip is used.

CHARLES R. COCHRAN.
